UNITED STATES PATENT OFFICE

100,744

DESIGN FOR A BOTTLE

Isaac Strouse, Baltimore, Md., assignor to The Baltimore Pure Rye Distilling Company, Dundalk, Md.

Application May 2, 1936, Serial No. 62,425

Term of patent 14 years

To all whom it may concern:

Be it known that I, Isaac Strouse, a citizen of the United States, residing at the city of Baltimore, State of Maryland, have invented a new, original, and ornamental Design for Bottles, of which the following is a specification, reference being had to the accompanying drawing, forming part thereof.

I claim:

The ornamental design for a bottle as shown.
In testimony whereof I affix my signature.

ISAAC STROUSE.
